INVENTOR

UNITED STATES PATENT OFFICE.

MAYME SCHULD, OF DETROIT, MICHIGAN.

UMBRELLA-HOLDER.

1,239,228.

Specification of Letters Patent.

Patented Sept. 4, 1917.

Application filed July 13, 1916. Serial No. 109,083.

To all whom it may concern:

Be it known that I, MAYME SCHULD, a citizeness of the United States, residing in Detroit, in the State of Michigan and the county of Wayne, have invented a new and useful article, an Umbrella-Holder, of which the following is a full, clear, and exact specification.

This invention relates to means for holding umbrellas.

The main object of the invention is to provide means of the character described, which shall securely hold the article placed in it, its simplicity of construction making it accessible to all, and permits easy insertion and withdrawal of the umbrellas.

Ancillary objects of the invention will appear hereinafter.

In the accompanying drawing, which illustrates the invention, Figure 1— is a side view of the umbrella holder, showing umbrella in position.

Fig. 2— is a top plan view of same.

Fig. 3— rounded rod for arms.

Fig. 4— side view of Fig. 3.

Fig. 5— back plate.

Fig. 6— side view of Fig. 5.

Fig. 7— front plate.

Fig. 8— side view of Fig. 7.

Referring to the drawings (1) is of the back or base plate being a flat metal piece. (2) is the front or cover plate having a raised groove in center which allows arms 3 to pass through. (3) designates a round

rod having the end portions bent into substantially U-shape to provide holding arms and having a flattened back 4 which when the plates are riveted together and arms are lifted presses against back plate 1 and rounded part of rod springs into groove 7 on front plate 2 and is held tight, (5) represents screws which holds holder on the end of seats pews wall or any flat surface. (6) represents rivets which hold front plate 2 back plate 1 and arms 3 together. (7) is rounded groove in front plate 2, (8) is opening in arms 3 which allows insertion or withdrawal of umbrella at will.

Having thus described my invention, what I claim as new is:—

An umbrella holder comprising a base plate, a longitudinally grooved spring cover plate adapted to be mounted upon said base plate, an umbrella holding member having a flattened body portion pivotally mounted in said groove and provided with curved ends with rebent extremities, said rebent extremities being spaced apart to receive an umbrella; said plates coacting with the said flattened members to hold the same in angular relation with the plates.

In testimony whereof I affix my signature in the presence of two witnesses.

MAYME SCHULD.
